(57) **CLAIM**

The ornamental design for a bed of a scanner for an x-ray tomography diagnosis apparatus, as shown and described.

DESCRIPTION

FIG. 1 is a perspective view of a bed of a scanner for an x-ray tomography diagnostic apparatus, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left-side elevational view thereof; and,

FIG. 7 is a right-side elevational view thereof.

The portions of the article depicted in lighter contrast form no part of the claimed design.

1 Claim, 7 Drawing Sheets
